UNITED STATES PATENT OFFICE.

JAMES DUDLEY MOORE, OF NORTH WILKESBORO, NORTH CAROLINA.

MECHANICAL MOVEMENT.

1,413,417.

Specification of Letters Patent. Patented Apr. 18, 1922.

Application filed September 2, 1919. Serial No. 321,093.

To all whom it may concern:

Be it known that I, JAMES D. MOORE, a citizen of the United States, residing at North Wilkesboro, in the county of Wilkes 5 and State of North Carolina, have invented certain new and useful Improvements in Mechanical Movements, of which the following is a full, clear, and exact specification.

This invention relates to a mechanical 10 movement, and more particularly to a mechanical movement for simultaneously oscillating or agitating a plurality of operative elements.

The invention has for its objects to provide a mechanical movement which will utilize a minimum amount of power for its 15 operation, will automatically take up any wear between the coacting elements, and also to provide a movement which will operate 20 quietly and efficiently.

The mechanical movement which will be described in this application was designed particularly for agitating the sieves or grain separating elements on flour mills, although 25 it should be distinctly understood that the invention is not limited in any way to this particular adaptation.

The objects of the invention are carried out in the present instance by means of a 30 member fixed to the drive shaft and provided with an eccentric groove. This member is adapted to cooperate with a second member disposed adjacent thereto and provided with a corresponding groove, the 35 groove in the second member, however, being concentric with respect to the inner and outer peripheries of said member. The second member is provided with an enlarged opening for the reception of the drive shaft and 40 a set of balls is interposed between the two members. Means, such as a spring, is provided to force the second member toward the first member, and as the drive shaft and the first member are rotated, this causes the

45 second member which is not rotated to oscillate in view of the eccentricity of the groove in the first-named member. The second member is operatively connected to the operative elements which are to be oscillated, 50 thereby communicating the oscillatory motion to these elements.

One embodiment of the invention has been illustrated in the accompanying drawings; and

55 Fig. 1 shows in perspective a flour mill

having my improved mechanical movement embodied therein;

Fig. 2 is a detail sectional view on an enlarged scale illustrating the improved mechanical movement;

Fig. 3 is a vertical sectional view of the member which is fixed to the drive shaft; and

Fig. 4 is a top plan view of a portion of the structure shown in Fig. 2.

In illustrating the present embodiment of the invention, the mechanical movement has been shown in connection with a flour mill, but as stated above, its use is not limited in any way to this machine.

A flour mill of the conventional type is shown in Fig. 1, this mill comprising a supporting base 10 having upright members 11 carried thereby, a casing 12 being mounted on the upright members 11 and enclosing the grinding mechanism.

A hopper 13 is supported above the casing 12 and is provided with a downwardly extending chute 14 which discharges into a screen or sieve 15. A discharge spout 16 leads from the 55 grinding mechanism and conveys the meal to a bolter 17 which is loosely supported at its front end by a flexible connection 18 which is secured at its upper end to a bracket 19 carried by the frame of the mill.

The mechanical movement which is claimed in this application is utilized in connection with the feed mill just described for oscillating the screen or sieve 15 and the bolter 17. This oscillating mechanism is carried by a shaft 20 supported in suitable bearings 21 carried by the uprights 11, and this shaft is driven by means of a pulley 22 which is connected by a belt to any suitable source of power.

Referring now to Figs. 2 to 4, inclusive, the details of the construction of the improved mechanical movement will be described.

The means for changing the rotary motion of the shaft 20 to an oscillating motion comprises a collar member 23 which is secured by a set screw 24 to the shaft 20. This collar is provided with a groove 25 which is formed eccentric with respect to the center 100 of the shaft 20, the eccentricity of the groove being clearly shown in Figs. 2 and 3. A second collar 26 is disposed adjacent the collar 23, this collar being provided with an enlarged or elongated opening 27 for the re- 105

ception of the shaft 20. The collar 26 is provided with oppositely extending flanges 28 and 29, the flange 29 overlapping an end portion of the collar 23. The main body 5 portion of the collar 26 is provided with a circular groove 30 which is formed concentric to the inner and other peripheries of the collar 26, the diameter of this groove being the same as that of the eccentric groove 25 10 formed in the collar 23. A plurality of balls 31 are mounted in the grooves 25 and 30, these balls being retained in the grooves and the collar 26 being maintained in a position adjacent the collar 23 by means of a 15 coil spring 32 which is interposed between the collar 26 and the casing 12. The inner bearing 21 for the shaft 20 is provided with an outwardly projecting shoulder 33, upon which one end of the coil spring 32 is positioned, the opposite end of this spring being positioned on the peripheral flange 28 which is formed on the collar 26. The oscillating movement of the collar 26 is communicated to the members to be oscillated thereby 20 25 by means of connecting links. The screen or sieve 15 is connected to the collar 26 by means of a link 34 which is pivoted at 35 to the collar 26, and at its opposite end passes through a rearwardly extending lug 36 carried by a pivoted member 37 which in turn is pivoted to a bracket 38 secured to the casing 12. The upper end of the member 37 is provided with an outwardly extending strap 39, preferably formed of resilient material, 30 35 the rear end of the screen being secured to this strap. The bolter 17 is connected to the collar 26 by means of a link 40 which is pivoted at 41 to the bolter, and at 42 to the member 26.

40 Having described the construction of my improved mechanical movement, I will now briefly outline the operation of the movement.

As the shaft 20 is rotated by means of 45 power communicated to the pulley 22, the collar 23 will also be rotated and will communicate oscillating movement in a plane perpendicular to the axis of collar 23 to the collar 26 by reason of the eccentric groove 50 55 25, balls 31 and groove 30. The spring 32 forces the collar 26 constantly toward the collar 23, thereby retaining the balls in position between the grooves 25 and 30. The oscillating movement of the collar 26 is communicated to the sieve or screen 15 by means of the link 34, pivoted member 37 and strap 39. This movement is also communicated to the bolter by means of the link 40 (see Fig. 4) which is pivoted at one end to the 60 65 bolter, and at its opposite end to the collar 26. This movement reciprocates the link 40 which in turn oscillates the bolter.

From the above description it will be seen that the construction has been provided in 65 which any wear between the members 23 and

26 will be automatically taken up by means of the spring 32, and also a construction which, by reason of the ball bearing driving connection, will utilize a minimum amount of power, and will communicate the movement from the shaft to the operative elements quietly and efficiently. 70

It will be evident also from the description that the mechanical movement described and claimed in this specification is equally 75 well adapted for other uses than that particularly shown in Fig. 1, or, in other words, that this movement is capable of general application.

While I have in the above specification described one embodiment of my invention, it should be understood that the invention is capable of modification, and that modifications and changes in the construction and in the arrangement of the cooperating parts 85 may be made without departing from the spirit and scope of the invention, as expressed in the following claims.

1. In a mechanical movement, a rotatable driving member, having an eccentric groove 90 therein, an oscillatory driven member disposed adjacent said first-named member and having a groove formed therein of a diameter corresponding to the groove in the first-named member, and means engaging said 95 grooves for communicating the movement of said first-named member to said second-named member.

2. In a mechanical movement, a rotatable driving member having an eccentric groove 100 therein, an oscillatory driven member disposed in a position adjacent said first-named member and having a groove therein of a diameter corresponding to the diameter of the first-named groove, a plurality of balls 105 disposed between said grooves and resilient means for retaining said second-named member in a position adjacent said first-named member.

3. In a mechanical movement, a rotatable 110 driving member having an eccentric groove therein, an oscillatory driven member having a groove corresponding in diameter to the groove of said first-named member and having a peripheral flange overlapping said 115 first-named member, a plurality of balls disposed in the said grooves, and resilient means for forcing one of said members in a direction toward the other member.

4. In combination, a driving member having an eccentric groove formed therein, a driven member having a groove formed therein corresponding in diameter to the groove of the first-named member, a plurality of balls disposed in the said groove, a 125 plurality of operative elements, and means for communicating the oscillating movement of the second-named member to said operative elements.

5. In a mechanical movement, a drive 130

shaft, a collar carried by said drive shaft and having a groove on its face formed eccentric with respect to the shaft, a non-rotating collar located on said shaft and having a groove formed on its face corresponding in diameter with the groove in the first-named collar, a plurality of balls disposed between

10 said grooves, and means for holding said second-named collar in a position whereby said balls will be retained in place between 10 said grooves.

In testimony whereof I affix my signature.

JAMES DUDLEY MOORE.
